UNITED STATES PATENT OFFICE.

HENRY O'B. HARDING, OF MINNEAPOLIS, MINNESOTA.

FILLED-BAG SEWING MACHINE.

Application filed May 15, 1920. Serial No. 381,643.

To all whom it may concern:

Be it known that I, HENRY O'B. HARDING, a citizen of the United States, residing at Minneapolis, in the county of Hennepin and State of Minnesota, have invented a certain new and useful Filled-Bag Sewing Machine, of which the following is a specification.

The present invention relates to a novel machine for closing the mouths of filled sacks, and is particularly related to machines designed for use in sewing sacks of relatively large size, where the weight of the same renders difficult their manipulation in the sewing operation. While intended primarily for the closing of sacks filled with flour, in connection with the packing of the flour into the sacks during the milling operations, the invention is capable of extended use and is adapted, therefore, to various other industries.

The main and primary object of the invention is to provide a machine of the character mentioned wherein is included a conveyer mounted to travel along the floor of a packing room in juxtaposition to the packing machines, and upon which the filled sacks are placed, as they leave the packing machine, for conveyance to the sewing machine. The weight of the sacks as they travel to the sewing machine thereby is borne by the floor, and the necessity for lifting the filled sacks for presentation to the sewing organization is eliminated.

A further object of the invention is the provision of a sewing machine of the character referred to the construction of which is such that the sewing organization may be adjusted with facility and ease in relation to the conveyer, whereby to adapt the machine for sewing bags of varying height or length, and without disturbing or disarranging the driving connections of the sewing organization, or altering the relation which the latter bears to the conveyer.

The invention further contemplates a filled-bag sewing machine having novel and efficient means for actuating and controlling the sewing organization. This enables the latter instantly to operate when the proper instrumentalities have been set by the operator, and to come instantly to rest at the completion of the sewing operation. Waste of thread, due to the uncontrolled momentum of the sewing organization after the

sewing operation has been completed, thereby is avoided, and the sewing organization is subjected to operating wear only for the period required for the formation of the stitches actually necessary for sewing the bags.

Other objects and advantages will appear as the nature of the improvements is better understood, the invention consisting substantially in the novel construction, combination and arrangement of parts hereinafter fully described, illustrated in the accompanying drawings, and finally pointed out in the appended claims.

The disclosure herein presents a practical embodiment of the invention and delineates to the art an appropriation of the concept to one of the uses to which the invention may be applied. It is to be considered, therefore, from an illustrative standpoint and not in a limiting or restrictive sense.

In the drawings—

Fig. 1 is a front elevation of a filled-bag sewing machine constructed in accordance so with the present invention.

Fig. 2 is a side elevation thereof.

Fig. 3 is also a side elevation, viewing the machine from the side opposite to that illustrated in Fig. 2.

Fig. 4 is a rear elevation of the machine pedestal, the adjustable carrier for the sewing mechanism, and the adjusting screw with which the carrier co-operates, the sewing mechanism and its adjuncts being omitted.

Fig. 5 is a fragmentary vertical sectional view through the adjustable carrier for the sewing mechanism.

Fig. 6 is a similar view, parts being in elevation, of the compound clutch incorporated in the driving connections for the sewing mechanism.

Fig. 7 is a detail elevation, on an enlarged scale, of the instrumentalities for actuating the thread-cutting mechanism and for locking the same in inoperative position.

Fig. 8 is a detail vertical sectional view on the line 8—8, Fig. 7.

Fig. 9 is an inverted sectional plan view on the line 9—9, Fig. 7.

Fig. 10 is a side elevation of the thread-cutter, on an enlarged scale.

Fig. 11 is a detail plan view thereof.

Fig. 12 is a detail sectional plan view of

the mechanism for controlling operation of the machine.

Fig. 13 is a detail perspective view of the head of the clutch shifting lever.

5 Fig. 14 is a fragmentary front elevation of the machine illustrated as equipped with another form of motor drive therefor.

Fig. 15 is a side elevation of the construction shown in Fig. 14.

10 As hereinbefore stated, the present invention contemplates a machine in which the filled bags are fed thereto by a conveyer which travels along the floor of a packing room, or other locality in which the machine is placed, which conveyer is located in such relation to the packing machines for feeding the commodity to the bags that the latter, when filled, may be placed upon the conveyer without the necessity of lifting 15 the same to any material elevation above the support on which they have been placed for filling. In the present adaptation of the machine, as also indicated, the same is designed for use in the closing of the mouths of sacks 20

25 filled with flour. The conveyer, therefore, traverses a path adjacent to the flour packing machines, and as the bags are filled thereby with the flour they are placed upon the conveyer and moved to the sewing machine, 30 which occupies a fixed position with respect to the conveyer. The numeral 10 designates the conveyer in question, this being of the endless belt type, and the stretch thereof on which the bags are placed bears directly 35 against the floor of the packing room and is supported thereby under the weight of the filled bags. This conveyer may be of any approved construction, and the same has a continuous motion imparted thereto by 40 driving mechanism independent of the mechanism for driving the sewing machine now to be described.

The numeral 11 designates a vertically disposed supporting pedestal, which pedestal 45 is provided with a base 12 that is bolted, or otherwise suitably connected, to the floor of the packing room, and at a point adjacent to one edge of the conveyer 10. Extending between the sides of the pedestal 11 is a connecting web 13, which web is provided with 50 a longitudinal slot 14 extending substantially the entire length of the web. By the formation of the slot 14 the side portions of the web 13 provide guides 15, and it is upon 55 these guides that the sewing organization presently to be referred to is designed to be vertically adjusted, whereby to occupy different positions with respect to the conveyer 10, and thus to be adapted for the 60 sewing of the mouths of bags of different height.

Associated with the pedestal 11 is a vertically adjustable carrier 16. This carrier 65 comprises a body plate 17 of substantial area, which plate fits snugly upon the face

of the web 13, said face and the opposing face of the plate 17 being properly machined to provide smooth surfaces designed to afford free sliding movement of the carrier 16 with respect to the pedestal. The edges 70 of the body plate 17 are provided with flanges 18 which gradually increase in size from the lower end of said plate to its upper end, and said flanges 18 are curved in a forward direction with respect to the pedestal 11 to provide an overhanging supporting head 19 to which a sewing head 20, of any approved construction, is attached. It will be observed, however, that the head 20 is so disposed that the needle thereof will operate in a horizontal plane, and thus across the mouth of the bag to be closed when the mouth thereof has been introduced between the feed mechanism and the presser foot of the sewing head. As the sewing head forms no part of the present invention, except that it constitutes broadly the sewing mechanism, it is unnecessary to describe the same in detail. 75 80 85

90 Adjacent to one side of the pedestal 11 is a vertically disposed control shaft 21. The lower end of this shaft extends through the floor which supports the pedestal 11, and its extremity is seated in a thrust bearing 22 which is fixedly mounted beneath said floor. 95 The shaft 21 is also received by a bearing bracket 23 which is carried by the pedestal 11, and against which a collar 24, carried by the shaft 21, is seated. The shaft 21 has a spline groove 25 formed therein, which groove extends substantially throughout the length of the shaft, the purpose of which will presently appear. The control shaft 21 has an oscillatory movement about its longitudinal axis, and this movement is utilized 100 in one direction for effecting application of power to the sewing mechanism, while its movement in the opposite direction is employed for effecting stoppage of the sewing mechanism, and also for operation of the 105 mechanism which is provided for severing the chain of stitches at the completion of the sewing operation. The shaft 21 is actuated by foot pressure applied by the operator of the machine, and by this means the 110 hands of the operator are free for use in introducing the mouth of the bag to the sewing mechanism and for guiding the bag when such is required. By referring to Fig. 115 120 the control mechanism for operation of the machine will be better understood. This includes a foot treadle 26 which is supported by an attaching yoke 27, said yoke having its stem 28 adjustably mounted in an attaching bracket 29 which is sleeved upon a supporting shaft 30, said bracket 29 being adjustably held on said shaft 30 by a set screw 31. The shaft 30 is mounted in bearings 32 properly supported beneath the 125 floor of the packing room at such a point 130

that the treadle 26 may project into a pit formed in the floor and in which the operator stands so as to be in convenient position to the sewing mechanism and the conveyer 5 for proper manipulation of the filled bags as they approach the sewing mechanism. Connected to one end of the shaft 30 is a sleeved attaching bracket 34, which is adjustably mounted on said shaft 30 by a set screw 35, and said bracket 34 has a connecting rod 36 adjustably mounted therein, as by a set screw 37, said rod 36 depending from said bracket 34 and extending downwardly therefrom for application to a connecting link 38. The ends of the link 38 are provided with attaching brackets 39 and 40, respectively, the bracket 39 being adjustably mounted on the rod 36, as by a set screw 41, and having a bifurcated end which receives the connecting link 38 and with which it is hingedly connected, as by a pin 42. The bracket 40 has its ends also bifurcated, but the bifurcations thereof are at right angles to each other, one of the same 25 receiving the end of the link 38, to which it is hingedly connected, as by a pin 43, while the other bifurcation receives the end of a lever arm 44 to which it is connected, as by a pin 45. The lever arm 44 is sleeved 30 upon the control shaft 21, being rigidly held thereon by suitable fastenings. Therefore, the shaft 21 is actuated by the lever arm 44 and the connecting link 38 upon depression of the treadle 26 to be shifted in one direction of rotation, and this is utilized for applying power to the sewing mechanism. At a point above the floor of the packing room, or the support on which the pedestal 11 is mounted, the control shaft 21 has mounted 35 thereon a second lever arm 46, said arm 46 projecting in an opposite direction to the lever arm 44, and said arm 46 has connected thereto one end of a spiral spring 47, which spring passes through the basal portion of the pedestal 11 and has its other end anchored to a fastening stud 48 carried by said pedestal. On the depression of the treadle 26 the spring 47 is placed under tension, the outward movement of the arm 46 away from the pedestal serving to accomplish this, and the power of the spring 47 is employed for returning the treadle 26 to its normal elevated position after pressure has been removed therefrom. Obviously, therefore, when the force of the spring 27 is thus applied the control shaft 21 is rotated in a direction opposite to that imparted thereto on the depression of said treadle. This serves to restore the operative parts thus far described to their normal position, and at the same time to interrupt the driving connections to the sewing mechanism, whereby the latter is brought to rest, and the chain of stitches 50 likewise severed as will later appear.

The control shaft 21 extends substantially throughout the length of the pedestal 11. It is received by a pair of perforated ears 49 carried by a bracket 50 fixedly connected to one side of the carrier 16, and said perforated ears 49 freely slide over the shaft 21 in the vertical movement of said carrier. Between the ears 49 is mounted a connecting sleeve 51, said sleeve having a feather connection (not shown) with the spline 75 groove 25 of the shaft 21. Thus, while said sleeve 51 is adapted to slide in a vertical direction along the shaft 21, it has no independent rotation thereon, and as the shaft 21 is oscillated the sleeve 51 moves therewith. Projecting from one side of said sleeve 51 is a connecting arm 52 the extremity of which has a loose pivotal connection with a depending shifting lever 53, the upper end of said lever 53 being curved and extending forwardly, and terminating in a connecting yoke 54. The upper end of said lever 53 is pivotally mounted or fulcrumed between a pair of upwardly extending ears 55, as by a pin 56, and as the lever 53 follows the oscillatory movement of the arm 52, due to the oscillation of the control shaft 21, the yoke 54 is raised or lowered. Arranged at the side of the carrier 16 at which the control shaft 21 is located is a 95 supporting bracket 57, said bracket being provided with an attaching foot 58 that is bolted to said carrier. The ears 55 are carried by said bracket, and extend upwardly therefrom, and the extremity of the bracket 57 opposite to the attaching foot 58 extends upwardly in parallel relation to the ears 55. Between the latter and the upwardly extending extremity of the bracket 57 is arranged a clutch ring 59 which is bolted to the 100 bracket 57 and sustained thereby in fixed relation thereto. The inner face of this clutch ring 59 is beveled, and said ring serves as a brake for effecting instant stoppage of the sewing mechanism when the power has been 105 disconnected therefrom. This will presently appear.

The supporting bracket 57 has a bearing 60 formed therein, which bearing receives a spindle 61 the lower end of which extends below the bracket 57. A pulley 62 is mounted on this extended lower end of the spindle 61, and a driving belt 63 is trained over this pulley and also over a driving pulley 64 carried by the armature shaft of an electric motor 65 that is fixedly connected to the carrier 16 so as to move with the latter. The motor 65 is controlled by any suitable switch mechanism (not shown) and is supplied with electrical current from any suitable source by proper wiring led to the motor.

At the upper end of the spindle 61 is a clutch cone 66, ball bearings 67 being interposed between the clutch cone 66 and the 130

opposing face of the supporting bracket 57. These balls are in contact with inserts of hardened metal, designated by the numerals 68 and 69, carried respectively by the cone member and said supporting bracket. The inserts 68 and 69 are annular in form, and constitute a raceway for the balls 67.

Interposed between the clutch cone 66 and the clutch ring 59 is a clutch shell 70. The faces of the flange of said shell 70 are beveled, and the face of the cone 66 is beveled to conform with the bevel of the shell 70. Sufficient space exists, however, between the clutch ring 59 and the clutch cone 66 for limited movement of the clutch shell 70 in relation to both of these elements. Consequently, when the shell 70 is moved into engagement with the cone 66 a driving connection is established therebetween, and the shell 70 operates with the cone. When, however, this connection is broken and the shell 70 is moved into engagement with the ring 59, movement of the shell 70 immediately ceases. The shell 70 has a centrally disposed upwardly extending sleeve 71 which is surrounded by a connecting ring 72, and said connecting ring 72 is provided at opposite points with outwardly extending studs 73 which are received by notches 74 formed in the extremities of the sides of the yoke 54. The upper end of the sleeve 71 is screw threaded and a clamping ring 75 is connected therewith and overlaps the connecting ring 72 to retain the latter in position on said sleeve. At the opposing faces of the connecting ring 72 and the clutch shell 70 are arranged annular inserts 76 and 77, which are of hardened metal, and interposed between said inserts 76 and 77 is a series of ball bearings 78. The inserts 76 and 77 constitute a raceway for these bearings. The shell 70 has a feather and spline connection 79 with a spindle 80, which is arranged in alignment with the spindle 61, but disconnected therefrom. The spindle 80 is journaled in a bearing bracket 81 bolted to one side of the overhanging head of the carrier 16, and at the upper end of said spindle 80, above the bracket 81, is mounted a pulley 82 over which is trained a driving belt 83 which passes around a pulley 84 carried by the sewing head 20. Thus it will be seen that when the spindle 80 is rotated by reason of a driving connection being established between the cone 66 and the shell 70 the sewing head is operated and this operation continues so long as the connection between said cone and said shell remains established. When, however, this is broken, and the shell 70 moves into engagement with the clutch ring 59 the operation of the sewing head is stopped instantly. This is due to the fact that the ring 59 serves as a brake for the clutch shell 70.

To provide against end thrust of the

spindle 80 a pair of collars 85 and 86 are carried thereby and arranged respectively above and below the bearing bracket 81.

For severing the line of stitches between successive bags the machine is equipped with suitable thread-cutting mechanism. This mechanism is located on the sewing head 20, and is arranged in such proximity to the stitch forming mechanism that the thread will be severed closely thereto in order to prevent undue waste of the thread. Figs. 10 and 11 illustrate in detail the thread-cutting mechanism, and by referring thereto the numeral 87 designates an elongated bearing screw which is in threaded engagement with the arm of the sewing head 20, said screw being of sufficient length to extend a substantial distance away from said arm. A pivoted cutter finger 88 is loosely mounted on said screw, being spaced from the adjacent portion of the arm of the head 20 by a washer 89. The pivoted cutter finger 88 is in co-operative relation with the throat plate 90 of the sewing head, and said throat plate 90 extends a slight distance beyond the arm of the sewing head to constitute a stationary cutter with which the finger 88 co-acts. Interposed between the head of the screw 87 and the cutter finger 88 is a coil spring 91 the pressure of which is exerted against the cutter finger 88 to maintain the latter in contact with the cutting edge of the throat plate 90. The cutter finger 88 has formed at one of its sides a pinion 92, and this pinion is engaged by the teeth of a segmental gear 93 pivotally mounted on a shaft 94 carried by a supporting bracket 95 associated with the arm of the sewing head 20. When, therefore, the segmental gear 93 is swung upon the shaft 94 the meshing of the teeth thereof with the pinion 92 causes the pivoted cutter finger 88 to swing into cutting relation with the co-operating end of the throat plate 90 for severing the chain of stitches, and for moving the cutter finger from its cutting relation with said throat plate, these movements being dependent upon the direction of movement of the gear 93. A connecting link 96 has pivotal engagement at one of its ends with the segmental gear 93, as at 97, and its other end has similar engagement, as at 98, with the upper end of a shifting lever 99 the lower end of which is pivotally connected, as at 100, with an attaching bracket 101 bolted to the body plate 17 of the carrier 16. The shifting lever 99 is arranged upon said body plate 17 in proximity to the side thereof at which the control shaft 21 is located. Associated with the sleeve 51, and projecting therefrom at the side thereof which is opposite to the arm 52, is a contact arm 102, said arm projecting through slotted openings formed in the bracket 50 and the flange 18 to which said bracket is bolted. The

contact arm 102 is located between the body plate 17 and the shifting lever 99, and to facilitate this positioning of said contact arm said lever 99 has a bowed portion 103. 5 At the extremity of the contact arm 102 an engaging finger 104 is pivotally mounted, as at 105. The finger 104 has a projecting tongue 106 which fits within a bifurcation 107 that is formed in the arm 102, and said finger 104 has a yielding movement in the direction away from the shifting lever 99, controlled by a leaf spring 108 arranged at the rear face of the contact arm 102. This yielding movement of the engaging finger 104 permits of yielding contact between the same and the shifting lever 99, so that if the movement of the arm 102, under the oscillation of the control shaft 21, is too great, breakage of the parts is prevented 15 by the yielding movement of the finger 104 when it engages with the lever 99. From the fact that the contact arm 102 is disposed at the side of the sleeve 51 opposite to the arm 52, it will be seen that the movement 20 of the latter, in swinging the lever 53 for application of the power to the sewing head, results in the contact arm 102 engaging the lever 99, and this causes the latter to swing away from the body plate 17 with a resultant forward movement of the connecting link 96 and swinging of the segmental gear 93 in a downward direction. This raises 25 the cutter finger 88 to inoperative position, and the chain of stitches formed by the sewing mechanism is not subject to the cutting action of the thread cutter. To sustain 30 the cutter finger 88 in this position a locking trip 109 is employed. This trip is in the form of a bell crank lever the longer arm of 35 which extends downwardly in a substantially vertical position, while the shorter arm thereof extends outwardly in a substantially horizontal position, and said locking trip 109 has a pivotal connection, as at 40 110, with an attaching bracket 111 bolted or otherwise suitably connected to the body plate 17. The horizontal arm of the trip 109 has an engaging shoulder 109' which co-operates 45 with a locking stud 112 arranged at the side of the shifting lever 99 and which projects over the shorter arm of the locking trip 109. A coil spring 113 is interposed 50 between the longer arm of the trip 109 and said body plate 17, and the pressure of this spring is utilized for urging the shorter arm 55 of the trip in an upward direction in order to maintain the shoulder 109' thereof in proper operative relation to the locking stud 112. When the shifting lever 99 is thrust forwardly by contact of the arm 102 therewith, the locking stud 112 is projected in a forward direction with respect to the locking trip 109, and when said stud has cleared the shoulder 109', the spring 113 causes the trip 60 109 to position the shoulder 109' in rear of said stud and thereby prevent return movement of the lever 99 until release of the trip 109 from engagement with the stud 112. This holds the cutter finger 88 in raised position during the operation of the stitch-forming mechanism. It is to be observed that the depending arm of the trip 109 is arranged between the body plate 17 and the engaging finger 104 of the arm 102. When, therefore, the arm 102 moves away from the lever 99 and towards the body plate 17 it engages the trip 109 and swings the depending arm thereof towards the plate 17. This depresses the shorter arm of the trip 109, against the pressure of the spring 113, 65 and frees the shoulder 109' from engagement with the locking stud 112. When this release takes place the shifting lever 99 immediately moves towards the plate 17 due to the action of a coil spring 114, one end 70 of which is connected to said plate 17 and the other end of which is engaged with a lug 115 carried by the lever 99 at the side thereof opposite to that whereon the locking stud 112 is located. The spring 114 is 75 of such strength that when it exerts its pull upon the lever 99 a quick action is imparted to the latter, and this causes the pivoted cutter finger 88 to snap downwardly into cutting relation with the throat plate 90 80 and thereby to sever the chain of stitches in the path of downward movement of said finger. At this time, as will be understood from the preceding description, there has been movement of the lever 53, under the 85 shifting action of the control shaft 21, to release the cone shell 70 from the clutch cone 66, and this obviously brings the sewing mechanism to rest. 90

It is desirable to limit the forward thrust 95 of the shifting lever 99, and to this end a stop 116, preferably in the form of a hook bracket, is bolted to the plate 17 so as to project in advance of the lever 99, and thereby restrict the forward movement of the latter. 100

It has been stated that the present invention contemplates also the provision of means for adjusting the sewing organization at varying points of elevation above the conveyor 10, thereby to adapt the machine for the sewing of filled bags of varying height or length. For this purpose there is associated with the pedestal 11, and fixedly mounted in the base 12 thereof, a vertically 105 extending adjusting screw 117. This screw is substantially the length of the pedestal 11, and is positioned therein in opposite relation to the slot 14. A guide plate 118 is arranged at the side of the web 13 which is 110 opposite to the side thereof at which the carrier 16 is located. This guide plate 118 is of sufficient width that its edges overlap the guides 15 of the web 13 and said plate 118 is adapted to travel vertically on said guides. 115

The plate 118 is connected at its top and bottom by a plurality of machine bolts 119 with the body plate 17 of the carrier, and said plates 17 and 118 are thereby held in embracing relation with respect to the guides 15. While the carrier and said plate 118 may move vertically on the pedestal 11, separation of the carrier from the pedestal is prevented by the plate 118 being positioned 10 at the opposite side of the web 13 to that at which the carrier is located.

The guide plate 118 is provided with an integral offset boxing 120, said boxing having at its upper and lower ends aligned 15 openings 121, and said openings receive the adjusting screw 117. Mounted on the screw 117 is an adjusting sleeve 122 the bore of which is screw threaded so as to correspond to and mesh with the threads of the screw 20 117. The length of this sleeve 122 is substantially coextensive with the interior of the boxing 120, and this provides a snug fit between the ends of said adjusting sleeve 122 and the ends of the boxing 120. As the 25 screw 117 is stationary, and thus incapable of rotation, the vertical adjustment of the boxing 120, and, perforce, corresponding adjustment of the carrier 16 by reason of its connection with the guide plate 118, is effected 30 by rotation of the sleeve 122 on said screw. This is accomplished by a bevel pinion 123 which is formed integral with the sleeve 122, which pinion meshes with a corresponding pinion 124 carried by a shaft 35 125. This shaft 125 is journaled in a tubular bearing 126 carried by an attaching plate 127 bolted or otherwise suitably fastened to the face of the body plate 17. For accommodating the pinion 124, the bearing 126 and 40 the shaft 125, the body plate 17 has an opening 128 formed therein, and said opening receives said parts to position the pinion 124 in intermeshing relation with the pinion 123. The shaft 125 projects beyond the attaching 45 plate 127 and is there provided with an operating crank 129 for its rotation. To obtain vertical movement of the carrier it is but necessary to rotate the crank 129 in the desired direction, whereupon the adjusting sleeve 122 is caused to travel along the 50 screw 117, and by reason of the arrangement of the sleeve 122 within the boxing 120 the carrier 16 will move upwardly or downwardly along the pedestal 11 in accordance 55 with the direction of movement of the crank 129.

For supporting the spool or spools of thread in proper relation to the sewing head 20 a thread carrier 130, of any approved 60 construction, is mounted upon the head of the carrier and suitable guides may be provided for training the thread to the sewing head.

From the foregoing description the operation 65 of the herein described bag closing

mechanism will be apparent, but briefly described it is as follows: The filled bags delivered from the packing machine or machines are placed upon the conveyer 10 and by the latter transported to the sewing machine. As the individual bags successively reach the sewing machine the mouth of each bag is presented to the sewing mechanism, it being understood, of course, that the speed of travel of the conveyer 10 is properly proportioned to the feeding mechanism of the sewing head so that the movement of the body of the bag will be such as not to interfere with the free feeding of the mouth thereof through the sewing mechanism. On 70 presentation of the advancing portion of the bag mouth to the stitch forming mechanism the operator depresses the treadle 26, which movement actuates the control shaft 21 so that the arm 52 actuates the lever 53 to depress the cone shell 70 into engagement with the clutch cone 66. It is, of course, understood that the motor 65 is constantly operating and thereby is affording continuous rotation to the clutch cone 66 through the driving belt 63. When the shell 70 thus is engaged with said clutch cone rotation is imparted to the spindle 80, the pulley 82 and the pulley 84 on the sewing head 20. The stitch forming mechanism of the head is 75 thus set into operation, and the mouth of the bag feeds through the sewing head and is closed by the stitch forming mechanism thereof. When the mouth has been completely closed the operator removes pressure 80 from the treadle 26, whereupon the spring 47 swings the control shaft 21 in the direction opposite to that effected by depression of the treadle 26, and this movement withdraws the contact arm 102 from engagement 85 with the shifting lever 99. At this time the engaging finger 104 swings against the locking trip 109 and depresses the short arm thereof from its engagement with the locking stud 112 carried by the lever 99. Instantly the pull of the spring 114 is exerted 90 on the lever 99, and by means of its connection with the segmental gear 93 through the link 96 said gear is moved upwardly, thereby 95 swinging the pivoted cutter finger 88 downwardly into co-operative cutting relation with the throat plate 90. A severance of the chain of stitches follows, and the filled bag with its mouth closed then passes away 100 from the sewing machine and is carried by 105 the conveyer 10 to a suitable point of delivery or distribution. When pressure has been removed from the treadle 26 the arm 52 rocks the lever 53 in the direction opposite to its movement when the treadle 26 110 was depressed, and in this rocking of the lever 53 the clutch shell 70 moves upwardly into contact with the clutch ring 59, which latter, as before described, serves in the capacity of a brake, and thereby brings the 115

clutch shell 70 instantly to rest. This immediately stops operation of the sewing head and prevents further feed of the thread therethrough, thus entirely eliminating waste of the thread which results from uncontrolled momentum of the sewing head following completion of the closing of the bag mouth. A noteworthy feature of the operation of the herein described mechanism is the fact that when the treadle 26 is depressed for application of the power to the sewing head there is immediate movement imparted to the pivoted cutter 88 of the thread cutting mechanism to raise the same to inoperative position, this being induced by contact of the finger 104 of the arm 102 with the lever 99 to thrust the latter forwardly and to permit locking engagement of the trip 109 with the stud 112 thereof, whereby to retain the pivoted cutter 88 in inoperative position during the entire operation of the closing of the bag; vice versa, when pressure is released from the treadle 26 to disconnect the power from the sewing head 20, the stitch-forming mechanism instantly comes to rest, due to the disconnection of the clutch shell 70 from the clutch cone 66, but simultaneously therewith the locking trip 109 is released from its engagement with the shifting lever 99, and the latter, induced by the action of the spring 114, instantly snaps the pivoted cutter 88 into cutting relation with the throat plate 90, thereby severing the chain of stitches at the time of removal 35 of the power from the sewing head.

In Figs. 14 and 15 is disclosed another form of motor drive for the sewing organization. This simplifies the construction of drive illustrated in the other views and 40 eliminates the belt connection between the motor and the spindle 61. The form disclosed in Figs. 14 and 15 includes an electric motor 131 supported from the carrier 16 by an attaching bracket 132, and which 45 is connected to the side of the carrier 16 at which the compound clutch is located. The motor 131, therefore, is directly below the compound clutch, and its armature shaft is arranged vertically so as to be in line with 50 the spindle 61 to which it is connected by any suitable form of coupling 133. This direct connection of the motor with the spindle 61 affords direct application of the power to that spindle, and the possibility of 55 displacement of the driving belt which extends from the motor to the spindle 61, as disclosed in the other form of drive herein shown, is overcome. In other respects, however, the drive of the sewing head by the 60 construction shown in Figs. 14 and 15 is the same as in the other form.

The entire sewing organization including its motor is supported by the carrier 16 and is movable therewith and by this arrangement 65 the entire sewing organization may be

adjusted with respect to the belt 10 which feeds the bags to the machine by simply manipulating the crank 129. In this movement of the carrier the connection of the sleeve 51 with the control shaft 21 is not 70 impaired as the sleeve 51, being splined to the shaft 21, may be adjusted vertically thereof without disturbing its capacity to swing with the shaft as the latter oscillates. Therefore, regardless of the height 75 of the bag, the sewing organization may be adjusted in relation to the same and the machine thus is adapted to be accommodated to varying sizes of bags.

I claim:

1. In a machine of the class described, the combination with a vertically disposed support, of a carrier slidably mounted thereon, a sewing organization mounted on said carrier and movable therewith, thread-cutting mechanism associated with said sewing organization, a source of power also carried by said carrier, control mechanism operatively related to said source of power for establishing driving connection between the latter and the sewing organization, and means actuated by said control mechanism for actuating the thread-cutting mechanism when the sewing mechanism has been rendered inoperative. 90

2. In a machine of the class described, the combination with a vertically disposed support, of a carrier slidably mounted thereon, a sewing organization mounted on said carrier and movable therewith, thread-cutting mechanism associated with said sewing organization, a motor carried by said carrier, control mechanism operatively related to said motor for establishing driving connection between the latter and the sewing organization, means included in said control mechanism for rendering the sewing mechanism operative and inoperative, and means actuated by said control mechanism for operating the thread-cutting mechanism when the sewing mechanism has been rendered inoperative, and for rendering the thread-cutting mechanism inoperative when the sewing mechanism is in operation. 105

3. In a machine of the class described, the combination with a vertically disposed support, of a carrier mounted thereon, means for actuating said carrier to adjustably position the same vertically of said support, a source of power carried by said carrier and movable therewith, a sewing organization also mounted on said carrier and movable therewith, thread-cutting mechanism associated with said sewing organization, and control mechanism operatively related to said source of power for establishing driving connection between the latter and the sewing mechanism, said control mechanism being operative to render the thread-cutting mechanism inoperative while 115 120 125 130 135

the sewing organization is in operation and to render the thread-cutting mechanism operative when the sewing organization ceases to operate.

4. In a machine of the class described, the combination with a support, of a carrier movable vertically thereof, a sewing organization mounted on said carrier and movable therewith, thread-cutting mechanism associated with said sewing organization, a source of power also carried by said carrier and adapted for constant operation, power-transmitting means interposed between said source of power and said sewing organization and adapted to render the latter operative and inoperative, control mechanism associated with said power-transmitting means and manually controlled, whereby to render the sewing organization operative and inoperative, and thread-cutting mechanism also associated with said sewing organization and governed by said control mechanism, whereby the thread-cutting mechanism is rendered inoperative during operation of the sewing organization and operative when the sewing organization has been rendered inoperative.

5. In a machine of the class described, the combination with a support, of a carrier movable vertically thereof, a sewing head mounted on said carrier and movable therewith, thread-cutting mechanism associated with said sewing head, a motor carried by said carrier, gearing connections between said motor and the sewing head for actuating the latter, means included in said connections for rendering the sewing head operative and inoperative, and control mechanism for governing actuation of the last mentioned means, said control mechanism also serving to govern actuation of the thread-cutting mechanism to render the latter inoperative when the sewing head is operative and operative when actuation of the sewing head has ceased.

6. In a machine of the class described, the combination with a support, of a carrier movable vertically thereof, a sewing head mounted on said carrier and movable therewith, thread-cutting mechanism associated with said sewing head, a motor carried by said carrier, gearing connections between said motor and the sewing head for actuating the latter, a clutch included in said gearing connections for rendering the sewing head operative and inoperative, control mechanism for governing actuation of the clutch, said control mechanism also serving to govern actuation of the thread-cutting mechanism to render the latter inoperative when the sewing head is operative and operative when actuation of the sewing head has ceased, and connections between said control mechanism and the thread-cutting mechanism, whereby when said control

mechanism renders the sewing head inoperative the thread-cutting mechanism is caused to operate and the thread-cutting mechanism rendered inoperative when the sewing head is brought into operation. 70

7. In a machine of the class described, the combination with a support, of a carrier movable vertically thereof, a sewing head mounted on said carrier and movable therewith, thread-cutting mechanism associated with said sewing head, a motor carried by said carrier, gearing connections between said motor and the sewing head for actuating the latter, clutch mechanism included in said gearing connections for rendering the head operative and inoperative, said clutch mechanism including a driving member, a brake member, and an interposed transmitting member connected to the sewing head and cooperating with the brake member to effect stoppage of operation of the sewing head, and control mechanism for governing actuation of the clutch mechanism, said control mechanism also serving to govern actuation of the thread-cutting mechanism 80 to render the latter inoperative when the sewing head is operative and operative when actuation of the sewing head has ceased.

8. In a machine of the class described, the combination with a support, of a carrier movable vertically thereof, a sewing head mounted on said carrier and movable therewith, thread-cutting mechanism associated with said sewing head, a motor carried by said carrier, gearing connections between said motor and the sewing head for actuating the latter, clutch mechanism included in said gearing connections for rendering the head operative and inoperative, said clutch mechanism including a driving member, a brake member, and an interposed transmitting member connected to the sewing head and cooperating with the brake member to effect stoppage of operation of the sewing head, and control mechanism for governing actuation of the clutch mechanism, said control mechanism including an oscillatory shaft, a rocking member connected thereto and to the transmitting member of the clutch mechanism, whereby to actuate the latter when said oscillatory shaft is operated, and means interposed between said oscillatory shaft and the thread-cutting mechanism for operating the latter, whereby 105 to render the thread-cutting mechanism inoperative during operation of the sewing head and operative when actuation of the sewing head has ceased. 110

9. In a machine of the class described, the combination with a support, of a movable carrier mounted on said support, means in juxtaposition to said support for conveying a filled bag to the support, a sewing head mounted on the carrier and movable there- 120 125 130

- with, thread-cutting mechanism associated with said sewing head, a motor carried by said carrier, gearing connections between said motor and the sewing head for actuating the latter, clutch mechanism included in said gearing connections for rendering the head operative and inoperative, said clutch mechanism including a driving member, a brake member, and an interposed transmitting member connected to the sewing head and cooperating with the brake member to effect stoppage of operation of the sewing head, and control mechanism for governing actuation of the clutch mechanism, said control mechanism including an oscillatory shaft, a rocking member connected thereto and to the transmitting member of the clutch mechanism, whereby to actuate the latter when said oscillatory shaft is operated, means interposed between said oscillatory shaft and the thread-cutting mechanism for operating the latter, whereby to render the thread-cutting mechanism inoperative during operation of the sewing head and operative when actuation of the sewing head has ceased.
10. In a machine of the class described, the combination with a support, of a carrier movable vertically thereof, a sewing head mounted on said carrier and movable therewith, thread-cutting mechanism associated with said sewing head, a motor carried by said carrier, gearing connections between said motor and the sewing head for actuating the latter, clutch mechanism included in said gearing connections for rendering the head operative and inoperative, said clutch mechanism including a driving member, a brake member, and an interposed transmitting member connected to the sewing head and cooperating with the brake member to effect stoppage of operation of the sewing head, and control mechanism for governing actuation of the clutch mechanism, said control mechanism including an oscillatory shaft, a rocking member connected thereto and to the transmitting member of the clutch mechanism, whereby to actuate the latter when said oscillatory shaft is operated, means interposed between said oscillatory shaft and the thread-cutting mechanism for operating the latter, whereby to render the thread-cutting mechanism inoperative during operation of the sewing head and operative when actuation of the sewing head has ceased, and latching mechanism cooperating with the last mentioned means to restrain movement of the thread-cutting mechanism during operation of the sewing head and to be released by the control means when the latter actuates the clutch mechanism to effect stoppage of the sewing head.
15. In testimony whereof I have hereunto signed my name in the presence of two witnesses.
